UNITED STATES PATENT OFFICE.

MAX BAUMAN, OF NEW YORK, N. Y.

DESIGN FOR A RING OR SIMILAR ARTICLE OF MANUFACTURE.

61,058.

Specification for Design.

Patented June 13, 1922.

Application filed January 12, 1922. Serial No. 176. Term of patent 3½ years.

To all whom it may concern:

Be it known that I, MAX BAUMAN, a citizen of the United States, and resident of the city of New York, borough of Manhattan, in the county and State of New York, United States of America, have invented a new, original, and ornamental Design for a Ring or Similar Article of Manufacture, of which the following is a specification, reference being had to the accompanying drawing, wherein—

Figure 1 represents a side view of a ring embodying my invention, and

Figure 2 an edge view of the same.

The main essentials of my design reside in the arrangement and disposition of the representations of bows and horseshoes symmetrically arranged relative to each other upon the collet of a ring.

What I claim and desire to secure by Letters Patent is:

The ornamental design for a ring or similar article of manufacture, as shown.

MAX BAUMAN.
